DISPOSABLE SYRINGE

Walter E. Ward, Berkeley, and Fred A. Cutter,
Oakland, Calif., assignors to Cutter Laboratories, Inc., a corporation of California

Application June 17, 1949, Serial No. 99,742

7 Claims. (Cl. 128—220)

1

This invention relates to a syringe, and particularly to one of the so-called disposable cartridge type.

Various substances must be injected into a human or animal body intramuscularly; the approved technique for effecting such an intramuscular injection is to force the sterile syringe hollow needle into the body at a desired location and, when the needle has attained the approximate depth desired, to apply a reduced pressure to the needle in an attempt to draw blood through the needle and into the syringe barrel; if it is possible to aspirate blood, then the needle must be relocated, the presence of blood being an indication that the needle is in communication with a blood vessel and is not within a muscle.

Various substances, of which penicillin is one example, are of such a viscous nature that they cannot be placed readily in the ordinary syringe; in addition, after use, the syringe must be cleaned with special solvents while if any moisture is present, a gum is formed; further, the ordinary syringe cannot be sterilized readily and is not suited to emergency or home use. For these and other reasons, many substances such as penicillin are most advantageously dispensed in a cartridge in conjunction with a syringe structure, the latter being thrown away after being used.

In the disposable cartridge syringes heretofore provided, the problem of aspirating has provided considerable difficulty and various involved techniques and relatively cumbersome devices have been employed. For example, one common form of device includes a removable rubber cap placed over the open end of the syringe barrel; when the needle is supposedly positioned intramuscularly, the rubber cap is worked in an attempt to provide an aspirating pressure upon the needle. The cap is of relatively small extent and the aspirating pressure applied is frequently not sufficient to give a true indication of the location of the needle end. Also, after the aspiration procedure has been followed, it is necessary to remove the rubber cap from the end of the syringe barrel, sterilize the cartridge, insert the cartridge in the syringe barrel, place the cap on the end of the cartridge, then effect the injection. Between the aspiration operation and the actual injection, the syringe barrel and needle can move because of the several manipulations which must be made while the attempt to insert the sterilized cartridge frequently results in what amounts to a relocation of the needle. This procedure is typical of the difficulties inherent in the use of various of the prior art syringes.

In accordance with the present invention, we provide a relatively simple and rugged disposable cartridge syringe which, because of its low cost and simplicity of operation, can be manufactured

2

at a relatively low cost and so can be thrown away after use. Briefly, the syringe of the present invention includes the combination of a hollow needle, a syringe barrel and a cartridge which, after removal of the usual sheath which protects the sterile needle, co-acts with the cartridge barrel as a piston to provide an aspirating pressure to determine if the blood can be drawn. Thus, the cartridge is inserted in the barrel by the manufacturer, and the entire syringe unit can be provided by the manufacturer as a sterile unit so that once it has been determined that the end of the hollow needle is in an intramuscular position, it is only necessary to move the cartridge to engage that end of the needle within the barrel to effect a discharge of the cartridge contents. In this way, the entire unit can be handled and the syringe does not have to be taken apart and reassembled while its hollow needle is supposedly in an intramuscular position.

It is in general the broad object of the present invention to provide a novel syringe of the cartridge type and which can be manufactured so inexpensively that, if desired, the syringe can be thrown away after use.

A further object of the present invention is to provide a novel syringe of the cartridge type which is particularly adapted to the intramuscular injection of such materials as penicillin and the like.

The invention includes other objects and features of advantage, some of which, together with the foregoing, will appear hereinafter wherein the present preferred form of syringe embodying the present invention is disclosed.

In the drawings accompanying and forming a part hereof, Figure 1 is a side elevation, partly in section, showing the device assembled but prior to use, while Figure 2 is a generally similar view, but showing the device in use.

Figure 3 is a side elevation partly in section through a modified form of the device.

Figure 4 is a plan view of the device shown in Figure 3.

Figure 5 is a side elevation partly in section, showing another form of the device as it appears during the manipulation.

Referring to the drawing, the device comprises a syringe barrel 6 having a suitable handle or grip portion made up of ears 7 extending transversely upon the upper end of the barrel 6. The lower end of the barrel is closed as at 8, and includes a projection 9 upon which is seated a removable sheath 10. The end 8 of the barrel 6 is fitted with an annular extension 11, the end of the sheath fitting between the extension 9 and the annular extension 11 in a sealing relationship. It is to be noted that extension 9 and extension 11 terminate in a common plane, the advantage of this being presently explained.

A hollow needle 12 is sealed in and extends through projection 9 and end 8 into the interior of the barrel 6, the needle being protected prior to use by the sheath 10. Within the barrel 6, a portion of the needle is surrounded by spaced annular extension 13, projecting upwardly within the barrel from end 8.

A cartridge of the material to be dispensed is generally indicated by numeral 21 and comprises a tubular member 22 having a transverse partition 23 therein dividing the cartridge into upper and lower portions. The material to be dispensed is indicated generally by numeral 24, being sealed in the lower portion of the cartridge by several closure discs 26.

The size of the cartridge 21 is such that it approximates closely the interior of the barrel 6; usually the barrel and cartridge are of circular cross section. In accordance with this invention, a ring 27 of a sealing material is provided about the lower end of the cartridge 21 and between the cartridge and the barrel 6 so that an effective seal is provided between the barrel and the cartridge and the cartridge acts as a piston in the syringe barrel.

In use, the unit is supplied by the manufacturer in that form in which it appears in Figure 1, the sheath being in place, the needle, the interior of the barrel and the end of the cartridge being sterile. When it is desired to inject the material in the cartridge, the sheath 10 is removed and first, the cartridge, if not already in such position, is moved toward the end 12 of the needle but is not engaged with such end so that an aspirating pressure can be later applied by retracting the cartridge with respect to the barrel and the needle 12 is forced into the desired location in a patient, usually until the flat and coplanar ends of extension 9 and ring 11 are against the patient's skin. The cartridge 21 is then moved rearwardly to apply an aspirating pressure to the interior of the needle to ascertain whether or not blood can be drawn. If blood can be drawn into the barrel, it is necessary to relocate the needle. If blood cannot be drawn into the barrel, then the needle is in position for the patient to receive the injection, whereupon the end of cartridge 21 is moved toward the patient, the projecting transverse ears 7 being grasped as between the middle and the forefinger and the end of the cartridge being forced inwardly by the thumb until the upper end 12 of the needle is forced through the several discs providing a closure within the cartridge 21. As the needle projects through the upper surface of the disc closure in the cartridge, the lower surface of the closure in the cartridge engages the upper end of extension 13, whereupon the cartridge closures are forced upwardly in the cartridge as a piston and the contents of the cartridge are forcefully projected through the hollow needle and into the patient, the cartridge being continually advanced to force additional material into the needle. The needle projects above the tubular extension 13 a distance only slightly more than the thickness of the cartridge closure discs and the extension 13 extends above the end 8 a distance slightly greater than the liquid depth in the cartridge so that the cartridge can be drained completely; the needle is sealed within the several disc closures so that leakage does not occur and the only release is through the hollow needle.

If desired, the barrel 6 can be supplied in sterile form, its end being closed with a suitable clo-

sure which is removed for use. Cartridge 21 can be supplied separately to fit the barrel with sufficient closeness as to permit of aspiration when the needle is positioned intramuscularly; in this case, the end of cartridge 21 is sterilized before insertion in the sterile barrel. Sealing means 27 can be carried by the cartridge, as we have shown in Figures 1 and 2, or by the barrel. Thus, in Figures 3 and 4, a rubber strip 31 is secured to ears 1, the rubber strip having an aperture therein which is slightly smaller than the diameter of the cartridge 21. Upon moving the cartridge 21, an aspirating pressure can be applied to the hollow needle 12, the rubber strip providing a gas-tight fit between the cartridge 21 and the barrel 6. In use, the barrel 6, needle 12 and cartridge 21 can be separately sterilized and barrel 6 used repeatedly with separate cartridges.

If aspiration is not considered necessary or desirable, then the seal 27 between the cartridge and the barrel need only be such as to ensure continuance of the sterile condition of the common areas. This can be achieved by providing an air filter medium between the two, as is indicated by numeral 20 in Figure 2, to remove any bacteria which might otherwise enter between the barrel and the cartridge; a suitable air filter is provided by felt, cotton, wax and the like.

In Figure 5 we have shown another form of the device embodying the present invention and in which a transparent barrel 41 is fitted with a removable needle structure 42 including a hollow needle 43 projecting into the transparent barrel 41. A tubular cartridge 44 is provided, this containing the material to be injected by the syringe, the cartridge being made up of a hollow tube, generally cylindrical in cross section, and closed at each end by slidably plugs 46 and 47. Adjacent to its upper end, the barrel 46 carries a sealing ring 48 which fits about the cartridge and provides a fluid-tight seal between the cartridge and the barrel. In use, the cartridge, barrel and the needle being sterilized, the needle is inserted in position for the injection, the cartridge being in place in the barrel but not in engagement with the end of the needle 43 which projects into the barrel. It is only necessary to retract the cartridge in the barrel to apply an aspirating pressure to the needle to ascertain if it is in an acceptable location for the injection. Once it has been ascertained that the needle is in an acceptable location, it is only necessary to move the handle structure, generally indicated by numeral 49, into a position in which plunger 51 therein is aligned with the barrel and with the cartridge. A cartridge lock 52 is then screwed into position, this being rotatably mounted in nut 53 and being engaged therewith by screw threads 54; the cartridge lock forces plug 46 into engagement with the projecting end of the hollow needle and the latter pierces the plug 46. When the cartridge lock is in position, plunger 51 is lowered into place to engage plug 47 and force it downwardly in the cartridge.

By providing projection 9 and the annular extension 11 of a length such that they terminate in a common plane, one using the syringe is provided with means for ascertaining both visually and by feel that the needle has been inserted to the correct depth; further, the annular extensions prevent too deep an insertion, it otherwise being possible to force projection 9 inadvertently into the flesh; additionally, the two provide a stable support for the syringe so it need not be held at all times when in position.

From the foregoing, we believe it will be apparent that we have provided a novel and simple form of syringe and of syringe cartridge which can be manufactured inexpensively and which enables an injection to be made very simply and with a materially simplified and yet adequate technique.

We claim:

1. A syringe comprising a barrel having an end and a tubular sidewall, a hollow needle having one end projecting from the barrel end and its other end projecting through the barrel end into the barrel, a tubular cartridge slidable in said barrel, means between said tubular cartridge and the tubular sidewall of said barrel providing a seal whereby said cartridge is slidable in said barrel as a piston in said barrel, a slidable closure in an end of said cartridge adapted to be punctured by an end of said needle, and a tubular extension extending into said barrel from said barrel end in a spaced relation to said barrel a distance slightly greater than the free depth of the cartridge and adapted to enter said cartridge and force the closure therein into the cartridge as a piston; said needle extending beyond said extension a distance slightly greater than the depth of said cartridge closure.

2. In combination, a cartridge comprising a tubular container having a sidewall and carrying a material for injection into a patient and having an open end closed by a puncturable closure; and a syringe for (1) ascertaining the suitability of a location for injection of the container carried material, and (2) injecting said material into a patient, the syringe comprising a tubular barrel having a sidewall, a hollow needle positioned with one end projecting into said barrel in a position to pierce said closure and the other end projecting beyond said barrel; and means engaging the cartridge sidewall with the tubular syringe barrel sidewall and slidably sealing the barrel and the cartridge and adapting the cartridge to cooperate with the barrel as a piston to apply an aspirating pressure to the hollow needle to ascertain whether or not the needle end is in a position wherein the cartridge contents can be injected into a patient.

3. In combination, a cartridge comprising a tubular container having a sidewall and carrying a material for injection into a patient and having an open end closed by a puncturable closure; and a syringe for (1) ascertaining the suitability of a location for injection of the container carried material, and (2) injecting said material into a patient, the syringe comprising a tubular barrel having a sidewall, a hollow needle positioned with one end projecting into said barrel in a position to pierce said closure and the other end projecting beyond said barrel; and means adapted to engage the cartridge sidewall with the tubular syringe barrel sidewall and seal the barrel and the cartridge to cooperate with the barrel as a piston to apply an aspirating pressure to the hollow needle to ascertain whether or not the needle end is in a position wherein the cartridge contents can be injected into a patient.

4. In combination, a cartridge comprising a tubular container carrying a material for injection into a patient and having one end closed by a puncturable closure and the other end closed

by a closure slidable in the cartridge as a piston; and a syringe for (1) ascertaining the suitability of a location for injection of the container carried material, and (2) injecting said material into a patient, the syringe comprising a tubular barrel, a hollow needle positioned with one end projecting into said barrel in a position to puncture said closure and the other end projecting beyond said barrel; means adapted to engage the cartridge with the tubular syringe barrel and seal the barrel and the cartridge together in a sliding gas-tight fit to adapt the cartridge to cooperate with the barrel as a piston to apply an aspirating pressure to the hollow needle to ascertain whether or not the needle end is in a position wherein the cartridge contents can be injected into a patient; and means for engaging the slidable closure to force said slidable closure to slide in said cartridge and eject the contents thereof through said needle when the one end of the needle projects through said closure.

5. A syringe comprising a barrel, a hollow needle having one end projecting from the barrel and its other end projecting into the barrel, a cartridge slidable in said barrel, an air filter between the cartridge and the barrel, a slidable closure in an end of said cartridge adapted to be punctured by an end of said needle, and a tubular extension extending from said end in a spaced relation to said barrel and adapted to enter said cartridge and force the closure therein into the cartridge as a piston.

6. A syringe comprising a barrel, a hollow needle having one end projecting from the barrel and its other end projecting into the barrel, a cartridge slidable in said barrel, an air filter between the cartridge and the barrel, a slidable closure in an end of said cartridge adapted to be punctured by an end of said needle, and a tubular extension extending from said end in a spaced relation to said barrel a distance slightly greater than the free depth of the cartridge and adapted to enter said cartridge and force the closure therein into the cartridge as a piston; said needle extending beyond said extension a distance slightly greater than the depth of said cartridge closure.

7. In a syringe of the class described, a barrel and a hollow needle projecting therefrom, a tubular cartridge containing a substance to be injected with said syringe and adapted to fit slidably in the syringe barrel and to cooperate with said barrel to force the contents of the cartridge through the hollow needle, and an air filter between the cartridge and the barrel.
